UNITED STATES PATENT OFFICE

GEORGE T. BRUUN, OF PITTSBURGH, PENNSYLVANIA, ASSIGNOR TO THE KOPPERS COMPANY, A CORPORATION OF DELAWARE

COKE-OVEN APPARATUS

Application filed March 3, 1928. Serial No. 258,833.

My invention relates to coke oven apparatus and particularly to means for indicating the condition or position of movable devices associated with coke ovens.

5 An object of my invention is to provide simple and effective means for signalling or indicating the position or condition of movable devices that are invisible from the location of the signalling devices.

10 A further object of my invention is to provide means visible on one side of a coke oven battery for indicating the position of a door or other apparatus on the other side of the battery.

15 A still further object of my invention is to provide means adjacent the pusher door of a coke oven for indicating whether the door on the coke side of the oven is in its open or its closed position.

20 In the operation of coke ovens, it is essential that, before the pusher ram operates to remove the finished coke from a coke oven, the operator be certain that the door on the coke side of the battery has been removed in order to avoid the damage to the oven structure that would result in case the door is broken from its fastenings upon the pushing of the oven. It has been the practice for each 25 of the operators of the door machines on opposite sides of the battery to rely upon the other's following a similar schedule both as to time and as to the order in which the ovens are pushed. Mistakes or delays have resulted in ovens being pushed before the doors on the coke side have been removed.

30 In accordance with the present invention, means are provided for indicating to the operator of the pusher ram whether or not the door on the coke side of any particular oven is in its open or its closed position. The indicating means may be operated either automatically upon opening the door or it may be operated manually, depending upon the type of signalling device that is employed.

45 Such signalling devices may be either mechanical or electrical, pneumatic or hydraulic, regardless of the specific character of the indicating device that is employed. Light reflections may also be employed. The operator may cause the ram to push the ovens

55 with complete assurance that the coke side door has been removed and in case the signalling devices are arranged for such purpose, he may be informed also as to whether or not the coke guide is in position to transmit the coke to the quenching car.

In the accompanying drawings,

60 Figure 1 is a view in vertical section of a battery of horizontal coke ovens with certain of its associated apparatus, parts being broken away;

65 Fig. 2 is an enlarged view of a portion of the structure of Fig. 1, parts being broken away;

70 Fig. 3 is an enlarged fragmentary view of a modification of the indicating apparatus of Fig. 2;

75 Fig. 4 is a vertical sectional view of a portion of a coke oven that is provided with a manually-operable indicating device;

80 Figs. 5 and 6 are end views, taken from the coke side and the pusher side, respectively, of the coke oven of Fig. 4;

85 Fig. 7 is a vertical sectional view of a portion of a horizontal coke oven provided with an automatically operated indicating device;

90 Fig. 8 is an end view of the coke oven and associated apparatus of Fig. 7;

95 Fig. 9 is a vertical sectional view of a portion of a horizontal coke oven that is provided with electrical means for indicating the position of a coke guide;

100 Fig. 10 is a vertical sectional view taken on line X—X of Fig. 9;

105 Fig. 11 is a diagrammatic view of a portion of the top of a coke oven battery arranged as illustrated in Fig. 9; and

110 Fig. 12 is a vertical sectional view of a portion of a coke oven battery that is equipped with a manually-operable electrical signalling device.

115 Referring particularly to Fig. 1, a coke oven battery 1 comprises a series of coke ovens having oven chambers 2, through one of which the sectional view is taken. The battery is provided with a top 3 having rails 4, upon which a larry car 5 operates to charge the ovens. An ascension pipe 6 at one end of each oven is connected to a collecting main 7.

Each oven chamber 2 is provided at its respective ends with detachable doors 8 and 9 that are removed when the coal in the oven has been completely coked. The doors 8 and 9 are located between the usual buckstays 10 that retain the side walls of the battery in position. The pusher side door 8 is usually removed by a door machine located on the usual pusher machine (not shown) that operates along the side of the battery. The coke side door 9 is removed by a door machine located on a car 12 that operates along the coke side of the battery.

The car 12 may also carry a coke guide 13 for guiding the coke from the oven into the usual quenching car. The coke is pushed by means of a pusher ram 14, only a portion of which is shown. A leveler bar 15, a portion of which appears, is ordinarily carried by the pusher machine and operates to level the coal when the ovens are being charged.

As shown in Fig. 1, and in enlarged detail in Fig. 2, the position of the coke-side door 9 may be indicated to the operator of the pusher machine by a mechanism operatively connected thereto. This mechanism comprises an arm 16 that is attached to the upper portion of the door 9 and which is normally engaged by a lever arm 17 that is pivotally supported on a bracket 18 and is connected at its upper end to a rod 19 that extends through a hollow pipe 20 transversely of the battery.

The hollow pipe 20 is provided at its threaded ends thereof with nuts 21 whereby the pipes 20 are substituted for the usual tie-rods for connecting the buckstays 10. On the pusher side of the battery, the rod 19 is provided with a vane or other indicating device 23 which may occupy either the extended position indicated by dot-and-dash lines or its retracted dotted-line position behind a shield 24 or other device, depending upon the position of the door 9 and the connected mechanism.

The lever 17 is provided with a weight 25 which operates when the door 9 is removed to move the lever 17 into its dotted-line position (Fig. 2) and thereby move the rod 19 to the right within the pipe 20 to expose the vane 23 to the view of the operator of the pusher machine. The operator may then be certain that the door 9 has been removed and that the corresponding oven may be safely pushed to remove the completed coke therein.

When the door 9 is again placed in position, the arm 16 engages the lever 17 and the latter is actuated from its dotted-line position to its full-line position (Fig. 2) and the rod 19 and vane 23 are actuated to the left, thereby indicating to the operator on the pusher side that the door 9 is in its closed position.

The foregoing operation has been described in connection with a single oven but it is typical of the operation of any oven in the battery. The ovens are normally pushed on

a definite schedule both as to their order and the time at which the operation is carried out. It will be appreciated that no time need be lost when the operator is ready to push the oven if the indicating device is in the position corresponding to the open position of the coke side door.

Reference may now be had to Fig. 3, in which a modification of the indicating device on the pusher side of the oven is illustrated. The rod 19 is provided at its right-hand end with a member 26 which engages an angular indicating device 27 that is pivotally mounted at 28 on a bracket 29 that is secured to the pipe 20.

The operation of this device differs from that of Figs. 1 and 2 in that the indicating device which normally occupies the position in which it is illustrated is actuated by the rod 19 to its dotted-line position when the door 9 is removed, as previously described. The position of the door 9 may be indicated by the position alone of the indicating device or the surface that is presented outwardly when it occupies its dotted-line position may be provided with a suitable legend, such as "Off" or "Open".

In the arrangement shown in Figs. 4, 5 and 6, a manually-operable handle 31 is connected to a rod 32 that is provided at the coke side of the battery with a rocker arm 33. The outer end of the rocker arm 33 is pivotally connected to two bell-crank levers 34 and 35 that normally are in alignment with the door 9 and constitute a barrier to its removal. However, when the door 9 is removed, the operator adjusts the handle 31 from its full-line position to its dotted-line position (Fig. 5) and the rod 32 actuates the rocker arm 33 downward to cause the lower ends of the bell crank levers 34 and 35 to separate and thereby permit the removal of the door 9 without any obstruction.

In the modification shown in Figs. 7 and 8, the arrangement is somewhat similar in principle to that of Figs. 1 and 2 in that the door 9 is provided with a projecting arm 37 that is adapted to engage a lever arm 38 that is controlled as to its position by a weight. The lever arm 38 is pivotally connected at 39 and is connected at its other end to a cable 40, which extends through a hollow pipe 20 and over suitable pulleys 41 and 42 on the coke side of the battery, and is provided at its outer end with a weight 43. The cable 40 is connected to a pivotally mounted member 44, which exposes or obscures legends "On" and "Off" as the case may be and thereby indicates the position of the coke side door 9. The device 44 is of such width that only one of the legends is visible in either of its positions.

In the arrangement shown in Figs. 9, 10 and 11, the car 46 for carrying the coke guide may be provided with the usual trolleys 47

for engaging the trolley wires 48 and, in addition, with a movable contact device 49 for controlling the circuits of electric lamps 50, respectively mounted adjacent the coke side door. The illumination of one of the lamps 50 through a circuit which comprises conductors 51 and 52 in an insulated conduit 53 indicates that the coke side door has been removed and that the coke guide is in alignment with the corresponding oven. The operator is thus informed that he may safely proceed with the pushing of the oven.

In the modification shown in Fig. 12, a manually-operable lever 55 operates a rod 56 through a hollow pipe 20 to control the position of a movable contact member 57 which opens or closes the circuit of an electrical signalling device, such, for example, as an electric bell 58. The contact member 57 may also control the circuit of the electric motor for operating the pusher ram.

It will be apparent from the foregoing descriptions of the various forms of my invention that coke oven batteries embodying one or more forms of the signalling devices may be operated expeditiously without danger of damage that might otherwise be caused by attempting to push an oven before the coke side door was removed. Other modifications may occur to those skilled in the art relating to the construction and operation of coke oven batteries and it is understood that my invention is not limited to the specific examples shown and described.

I claim as my invention:

1. In a battery of horizontal coke ovens, a removable door on one side of said battery and means comprising a signal device on the other side of the battery for indicating the position of said door.

2. The combination with a coke oven having a removable door at each end thereof, of an indicating device adjacent one of said doors and operatively connected to the other of said doors to indicate the latter door's position.

3. The combination with a coke oven having a door at each end thereof, of an indicating device adjacent one of said doors, and means for operating said indicating device in accordance with the position of the other door.

4. In a battery of horizontal coke ovens, doors for each of said ovens on opposite sides of the battery, and means adjacent the pusher side door and operatively connected to the coke side door for indicating the position of the latter door.

5. In a battery of horizontal coke ovens, frame members on opposite sides thereof, hollow members for connecting said frame members, a movable device on one side of said battery, a signal device on the other side of said battery, and means within one of said hollow members for controlling said signal

device to indicate a predetermined position of said movable device.

6. In a battery of horizontal coke ovens, frame members on opposite sides thereof, hollow members for connecting said frame members, a movable device on one side of said battery, a signal device on the other side of said battery, and means comprising a member movable within one of said hollow members for controlling said signal device to indicate a predetermined position of said movable device.

7. In a battery of horizontal coke ovens, frame members on opposite sides thereof, hollow members for connecting said frame members, removable doors at the respective ends of each oven on opposite sides of the battery, a movable device adjacent each pusher side door, and means extending through said hollow members and operatively connected to the coke side doors for controlling the position of said devices according as the corresponding coke side door is in its open or its closed position.

In testimony whereof, I have hereunto subscribed my name this 2nd day of March, 1928.

GEORGE T. BRUUN.
